UNITED STATES PATENT OFFICE.

FRANK DVORAK, OF DICKINSON, NORTH DAKOTA.

MAGAZINE-HAMMER.

1,204,960.

Specification of Letters Patent. Patented Nov. 14, 1916.

Application filed April 15, 1916. Serial No. 91,423.

To all whom it may concern.

Be it known that I, FRANK DVORAK, a citizen of the United States, residing at Dickinson, in the county of Stark and State 5 of North Dakota, have invented certain new and useful Improvements in Magazine-Hammers, of which the following is a specification.

This invention relates to an improved 10 magazine hammer and the principal object of the invention is to provide a hammer having an improved type of nail holding compartment or chamber adjustably mounted and to further provide improved means for 15 feeding nails out of the compartment.

Another object of the invention is to provide improved means for adjusting the position of the nail holding compartment and to also provide improved means for actuating 20 the revolving cylinder for feeding the nails out of the compartment, the actuating means for the cylinder being connected with an abutment bar so that the abutment bar will move in timed relation to the cylinder.

25 Another object of the invention is to so construct the mechanism for actuating the abutment bar and cylinder that it will be yieldably held in a normal position.

This invention is illustrated in the accompanying drawings wherein:—

Figure 1 is a view showing the magazine hammer in side elevation. Fig. 2 is a view showing the hammer in longitudinal section. Fig. 3 is a view showing the hammer in top plan. Fig. 4 is a fragmentary sectional view showing the manner of mounting the feeding cylinder. Fig. 5 is a vertical sectional view through the frame in which the tube carrying the cylinder is mounted. Fig. 40 6 is a view in side elevation of the tube and cylinder. Fig. 7 is an end elevation of the nail receptacle. Fig. 8 is a perspective view of the latch plate for releasably holding the adjusting strip in a set position. Fig. 45 9 is a perspective view of the adjusting strip for the nail holder. Fig. 10 is a perspective view of the rocker arm connected with the trigger of the hammer. Fig. 11 is a perspective view of a device for temporally holding the nails in the passageway formed in the head of the hammer. Fig. 12 is a fragmentary sectional view showing the tack holder of Fig. 11 mounted in the hammer head.

55 This hammer is provided with a handle 10 and head 11 above which there is located a

housing 12. This housing 12 is provided at its forward end with an extracting head 13 which is located above the driving head 11, and has its forward end formed into hinge 60 ears 14 between which are pivotally mounted, the hinge ears 15 of the supporting plate 16 so that when the pin 17 is in place, the supporting plate will be movably mounted and may be swung outwardly. 65

Within the housing 12 which is provided with a sliding closure 18, there is positioned a nail supporting rack or frame 19 formed from U-shaped strips connected as shown in Fig. 7 to provide arms 20, 21 and 22. The 70 upper ends of these arms are flared thus providing means for supporting nails between the arms 20 and between the arms 21 and 22. Tongues 24 and 25 extend rearwardly from the nail supporting frame as 75 shown in Fig. 2 with the tongue 24 resting upon the tongue or lip 26 and a securing pin or bolt 27 is passed through the tongues 24, 25 and 26 to releasably and pivotally mount the frame. An adjusting strip 28 extends 80 beneath the frame between the abutment tongues 29 and is provided with an opening 30 through which the pin 27 passes to pivotally mount this adjusting strip thus permitting the nail frame to be shifted to the 85 proper position in the housing 12 when desired. An actuating handle 31 extends upwardly from the outer end of this adjusting strip to facilitate swinging movement of the strip and from the opposite side of 90 the outer end of this strip there extends a tooth 32 which will fit into a selected one of the notches 33 formed in the overhanging flange 34 of the latch plate 35. After the nail holding frame has been moved to the 95 desired position with the outer end portion of the adjusting strip compressed to permit swinging of the strip, the strip will be released and the spring 36 will return it to the normal position thus moving the tooth 100 32 into one of the notches 33 of the flange 34.

A frame or supporting bracket 37 is secured to the plate 16 by means of rivets 38 and carries a casing 39, one portion of which forms a tube 40 for permitting nails to pass down into the passageway 41 of the driving head 11. A feeding cylinder 42 is rotatably mounted in the casing 39 as clearly shown in Fig. 4 and is provided with a pocket 43 to receive the nail which passes 105 into the casing through the inlet slot 44 of the supporting bracket 37. This feeding

cylinder 42 carries a gear 45 which meshes with a gear carried by the shaft 46 and which in its turn is provided with a gear engaged by the teeth of the rack bar 47. 5 The rack bar 47 extends through the housing 12 to one side of the nail holding rack or frame 19 and is connected with the rocker arm 48 by means of the link 49. The lower end of this rocker arm 48 is connected with the trigger rod 50 and therefore when the 10 trigger rod 50 is drawn to move the abutment bar 51 outwardly, the rack bar 47 will be moved to rotate the cylinder 42 and deposit a nail in the tube 40 through which it will pass into the passageway 41. A 15 spring 52 is provided to prevent the nail from dropping out through the passage way 41 but permit the nail to pass through this passage after it has been started in the wood. 20 When the trigger rod 50 is released, the spring 53 which is mounted upon pin 54 will return the rocker arm 48 to its normal position, thus rotating the cylinder and returning it to the position shown in Fig. 2 and at 25 the same time moving the abutment bar 51 across the upper end of the passage 41 so that when the nail strikes the work, the head of the nail will hit against this abutment bar and permit the nail to be driven into the 30 work a short distance. The nail can then be drawn out through the passage way 41, and can be driven into the work as far as desired by striking with the driving head 11.

When in use the nails are placed in the 35 supporting frame and if desired three sizes of nails can be placed in this frame, the frame will be moved to feed the proper size nail into the pocket of the cylinder 42 and the trigger will then be pulled rearwardly 40 thus feeding a nail into the passage 41 while the abutment bar is moved out of the way. The abutment bar will then return to the position shown in Fig. 2 when the cylinder returns to the normal position for receiving 45 a second nail and the nail can be driven into the work as already described.

Therefore the nails can be easily fed out of the hammer and various sizes can be carried in the nail compartment. If desired, 50 the spring 52 can be done away with and the nail holder shown in Fig. 11 used. This nail holder includes an anchoring tube 55 having arms 56 extending therefrom, bowed outwardly to provide a passage 57 through 55 which the nails will pass. This device will be placed in the driving head with the arms extending transversely of the head and the pocket 57 positioned in the passage 41. Therefore the nails will pass through this 60 pocket and will be releasably held therein by the spring action of the arms 56.

What is claimed is:—

1. A magazine hammer comprising a handle, a driving head carried by said handle 65 and provided with a passageway, a housing

carried by said handle, a wall extending adjacent said housing, nail holding means in said housing, a supporting bracket carried by said wall, nail feeding means rotatably connected with said bracket for conveying 70 nails from said holding means and depositing the same in the passage way of said driving head, an abutment bar slidably mounted in said driving head and extending across the passage formed therein beneath said 75 feeding means when in a normal position, an operating handle for said abutment bar, and actuating means for said feeding means connected with said operating handle for imparting movement to the conveying means 80 when the abutment bar is moved.

2. A magazine hammer comprising a handle, a driving head carried by said handle and provided with a passageway, a housing carried by said handle above said driving head, feeding means rotatably mounted above the passageway for conveying nails from said housing and depositing the same in the passageway of said driving head, an abutment bar slidably mounted in said driving head for extending across the passageway formed therein beneath said feeding means, operating means for said abutment bar, and actuating means for said feeding means connected with the operating means 95 of said abutment bar for operating the feeding means in timed relation to the movement of said abutment bar.

3. A magazine hammer comprising a handle, a driving head carried by said handle 100 and provided with a passageway, a housing carried by said handle above said driving head, a supporting bracket positioned in front of said housing, a sleeve carried by said bracket and providing a conduit positioned above the passageway in said driving head and having an open lower end, a feeding cylinder rotatably mounted in said sleeve and provided with a pocket communicating with said housing when the cylinder 105 is in a normal position and communicating with said conduit when the cylinder is rotated for depositing a nail in the conduit, an abutment bar slidably mounted to extend across the passageway of said driving head, 110 operating means for said abutment bar for drawing the same from across the passageway, and actuating means for rotating said cylinder connected with the operating means of said abutment bar for moving the cylinder 115 in timed relation to the movement of said abutment bar.

4. A magazine hammer comprising a handle, a driving head carried by said handle and provided with a passageway, an abutment bar slidably mounted to extend across the passageway and having an operating stem forming a trigger, a housing carried by said handle above said driving head, rotatable feeding means mounted in front of said 125 130

housing and above the passageway of said driving head, and actuating means for said feeding means including a rocker arm pivotally mounted in said handle and pivotally connected with the trigger of said abutment bar, a rack bar slidably extending through said housing, a link pivotally connected with said rack bar and pivotally connected with said rocker arm, and means yieldably holding the rocker arm in a normal position with the abutment bar extending across the passageway of said driving head and the feeding means in a position to receive a nail from said housing.

15 5. A magazine hammer comprising a handle, a driving head carried by said handle and provided with a passageway, a housing carried by said handle, a nail supporting frame in said housing formed of a plurality of U-shaped strips positioned one within the other to provide nail supporting arms, tongues extending from one of said strips, a

pin extending through said tongues to pivotally mount the nail holder, abutments extending from said strips, an adjusting rod 25 extending between said abutments and pivotally mounted by said pin, the outer end of said adjusting rod being provided with a handle and with a tooth, a latch plate carried by the hammer handle and provided with notches to receive selectively the tooth 30 of said adjusting rod to releasably hold the rod in position and thus to retain the nail holder in a set position, feeding means positioned in front of said housing and above 35 the passageway in said driving head, and actuating means for said feeding means.

In testimony whereof I affix my signature in presence of two witnesses.
